2,028,084

GLUE CONTAINER AND SPREADER

Stephen A. Brown, Chicago, Ill., assignor to
Joseph Boehler, Chicago, Ill.

Application April 3, 1933, Serial No. 664,183

5 Claims. (Cl. 91—67.4)

My invention relates to a class of devices employed in the application of liquid or semi-liquid adhesive materials, or plastic adhesive materials of sufficiently low viscosity to surfaces that are to be secured to the same or similar surfaces such as, for example, wrapping paper, closures for boxes or cartons, hinged covers for cardboard and paper boxes, wall papers, posters, labels, etc. More particularly, this invention relates to the combination of an improved glue container and spreader.

Among the objects of my invention are to provide a container for glue, mucilage or similar adhesives, which is practically air and water tight; second, to provide a receptacle so constructed that its contents will not be discharged if it is upset in any way; third, to provide a portable and at all times readily usable means for supplying and distributing liquid adhesives; fourth, to provide a container that will supply a regulable amount of effluent at all times, preferably in a thin coating; fifth, to provide in combination with such glue container a spreading attachment for distributing and levelling the adhesive material discharged from the container when in use; sixth, to provide a device wherein the amount of effluent issuing from the container is controlled by the amount of the opening between the spreading attachment and the outlet of the container; seventh, to provide a device with a manual control over the combined operations of discharging and spreading the liquid adhesive; eighth, to provide a device wherein the amount of effluent is also regulable by a positive stop which may be adjusted and permanently set in various positions to permit desirable amount of opening between the spreading attachment and the outlet of the container; ninth, to provide a device wherein the spreading attachment automatically seals the outlet of the liquid container when the device is not being used; and lastly to provide as a whole a novelly constructed glue containing and distributing device which is particularly simple, durable and economical of construction, requiring a minimum amount of maintenance, and one which will not permit its contents to become oxidized or dried when not in use, to spill or overflow when upset in any way, to become diluted to a point beyond use when the device might be immersed in a body of water which is customary practice among operators when the device is not being used.

These and other objects of my invention consisting of novel features of construction, combination and arrangement of parts will appear in

that part of the specification following wherein the features are described in detail and will be more clearly understood by reference to the attached drawing in which:

Fig. 1 is a side elevational view of the improved glue container and spreader tilted back in the position which it would assume when not in use and left standing on a horizontal surface.

Fig. 2 is a sectional view in elevation of the device clearly showing the opening between the roller and spout of the glue pot as the apparatus is drawn over the surface being treated.

Fig. 3 is a front elevational view of the device.

Referring to the drawing, No 1 indicates the container which is a hollow aluminum casting 15 having a handle 2 suitably joined to and spaced from the container 1 by a plurality of posts 3. The adhesive materials are charged into the receptacle through circular opening 4 which is covered by cap 5 and held tightly in place over opening 4 by means of a spring 6 which projects into the posts 3 under shoulders 7. The liquid adhesive pours through the opening 8 out of spout 9 when the roller 11 is separated from the concave seat of spout 9 of the container 1. The curvature of this seat is such as to provide a snugly fitting seat for the roller when the two are in contact with each other. An integral foot 10 is shown as a part of the aluminum casting comprising the container and is located between the middle and spout-end of the base so that when the device is placed on a horizontal surface it tilts backward permitting the sealing of the spout 9 by means of roller 11 under pressure of spring 26 after release of pressure on grip lever 23.

Roller 11 is preferably made of rubber and journaled on a rod 12 extending between side arms 13 and 13' of an aluminum casting 15. Side arms 13 and 13' constituting the ears of the aluminum casting 15 are pivoted on their respective sides to the hollow aluminum receptacle by screws or trunnions 14 and 14'. Aluminum casting 15 is pivoted and joined by means of pin 16 to collar 17 which is drilled and threaded to receive the threaded end of rod 18.

Rod 18 which controls the movement of the aluminum casting 15 and serially in turn that of the side arms 13 and 13' and ultimately the movement of roller 11 to and from spout 9, extends upwards through a jaw-like piece 19 which is an extension of handle 2, passing therethrough to be joined by pin 21 to the extension 20 of grip lever 23 which operates as a lever about the fulcrum and pivot pin 22. On the upper end of this

rod 18 are the parts which regulate the adjustment and set the stop, which in turn controls the amount of opening between the rubber roller 11 and spout 9 when the device is in use. These 5 consist of a lock nut 24 for holding the adjusting nut 25 in a set position. The adjusting nut 25 carries a sleeve 27 which houses the spring 26. Sleeve 27 moves with the adjusting nut 25 as an integral part thereof and may or may not contact washer 28 depending on the setting of the 10 adjusting nut 25, while the spring 26 constantly bears against washer 28 regardless of the position of the adjusting nut.

In preparing this glue container and spreader 15 for use the cap 5 is removed and adhesive material is charged into receptacle 1 through opening 4. After filling the container the cap is sprung into place and securely fastened over the opening by spring 6, the extensions of which fit grippingly 20 under the shoulders 7-7 of posts 3-3. The next preparatory step is the determination of the size 25 of opening that will be required between roller 11 and spout 9. This depends upon the viscosity and general characteristics of the adhesive material employed and also on the thickness of the application of same that the operator desires to spread on the surface to be treated.

By setting adjusting nut 25 the free movement 30 of rod 18 is limited which limited motion is translated through several movable parts to the roller 11 which in turn is only allowed a limited recession from spout 9. All the aforementioned movable parts are controlled and set in motion by the movement of the lever arm 23 in the grip of 35 the operator. Thus when the adjusting nut is secured by means of locknut 24 at a low point on rod 18 there will be a relatively wide recession of the roller from the spout under the full movement of lever 20-23. By depressing handle 23 to the 40 limit rod 18 will rise through jaw-like opening 19 until sleeve 27 strikes washer 28. In rising rod 18 will lift crosspiece 15 and in turn swing roller 11 away from spout 9. On the other hand if the 45 adjusting nut is set higher up on rod 18 the recession of the roller from the spout will be proportionately less. It will be apparent to those skilled in the use of mechanisms of this type that the recession of the roller from the spout is proportional to the distance between the edge 50 of the sleeve 27, which is an integral part of the adjusting nut, and the washer 28, if the operator grips the handle 2 so as to continuously depress lever 23 to the limit during use.

The fine screw adjustment of the amount of 55 opening between the spreading roller and the spout of the container is a special feature of the invention. The operator is instructed to grip the handle of the device firmly in such a manner that the lever arm 23 is depressed to the limit. The 60 simplicity of construction and operation of the glue spreader is such that aside from the above instruction the operator is not called upon to exercise any judgment as to the amount of glue he deposits on the surface being treated or the manner he should spread the deposited material about 65 the surface. By merely pulling the device lightly across the surface a uniform amount of adhesive, predetermined by the setting of the fine screw adjustment, will be automatically deposited 70 from the open spout, and spread by the rubber roller, along the entire length of the surface treated or, on as many surfaces desired, as long as the container holds a supply of adhesive. By reason of this automatic regulation of discharge and spreading of glue most of the human error usually 75

to be reckoned with among operators in shipping and wrapping departments is avoided, permitting more time for better and more uniform applications and sealing of packages.

The container itself is a distinct improvement 5 over many such on the market used for similar purposes in that so long as it contains adhesive material it is always ready for use on any type of glue-coating work. The aluminum casting comprising the receptacle has only a circular 10 charging port on top and the outlet spout along the lower front edge as openings for the possible loss of material or introduction of air or water. These openings are securely closed respectively by the cap which is sprung over the charging 15 port and held in place by the spring, and the rubber roller which is held fast on the seat of the spout by the spring 26 after the operator releases his grip on the handle 2 and lever 23. Thus sealed up in the practically air tight receptacle the adhesive material will not be exposed to the drying or hardening influence of air nor will it absorb or become diluted with water when immersed in a body of water when not in use. Likewise any accidental loss of control over the apparatus 20 will not result in a discharge of its contents about the premises. Lastly the prompt sealing of the spout upon the operator's release of pressure on the grip-lever, although still holding the device aloft, prevents the objectionable dripping of adhesive material over the packages, work bench and floor in the vicinity of the operator.

As described this disclosure relates to a portable manually operated glue container and spreader but it is also within the scope of the invention to 35 use this device for distributing any type of adhesive material that will flow through the elongated narrow opening in the spout. Also the device disclosed may be advantageously made an integral part of a machine operated glue applicator.

I claim as my invention:

1. A container for liquid or semi-liquid materials having an opening in the top for charging materials thereto, a narrow opening along the 45 lower front edge for discharging materials therefrom, said lower front edge terminating in protruding lips shaped to fit a moveable closure for said narrow opening comprising a roller adapted to seal said narrow opening when held against 50 said protruding lips and a foot integral with the bottom of said container.

2. In combination, a container for adhesive fluids having an opening in the top for charging adhesive materials thereto, a tight fitting removable closure for said opening, a narrow opening along the lower front edge of said container for discharging materials therefrom, said lower front edge terminating in protruding lips shaped to fit a moveable cylindrical closure for said narrow 60 opening comprising a roller adapted to seal said narrow opening when held against said protruding lips a supporting means for said moveable cylindrical closure attached to the body of said container, and a foot integral with the bottom 65 of said container.

3. In combination a dispensing container for fluid substances including a hollow receptacle having an opening in the top for introducing fluid materials thereto, a tight fitting removable closure for said opening, a transporting handle integrally connected to the top of said hollow receptacle by front and rear posts, a protruding lower front edge containing a narrow opening extending substantially the full length of and parallel to 70

5 said lower front edge, a rotatable and displaceable cylindrical closure for said narrow opening, a supporting means for said cylindrical closure pivotally fastened to said receptacle, and a foot integral with the bottom of said receptacle near its lower front edge.

10 4. In combination a dispensing container for fluid substances including a hollow receptacle having an opening in the top for introducing fluid materials thereto, a tight fitting removable closure for said opening, a transporting handle integrally connected to the top of said hollow receptacle by front and rear posts, a protruding lower front edge containing a narrow opening 15 extending substantially the full length of and parallel to said lower front edge, a rotatable and displaceable cylindrical closure for said narrow opening, a supporting means for said cylindrical closure pivotally fastened to said hollow receptacle, a threaded connecting rod pivotally connected at one end with said supporting means for said cylindrical closure, a thumb screw with extended sleeve surrounding a portion of said con-

necting rod, a spiral spring also surrounding a portion of said connecting rod and itself surrounded by said extended sleeve, a two arm lever pivotally connected with the other end of said connecting rod and also pivotally connected with 5 said transporting handle.

10 5. A glue applicator comprising a receptacle having a charging port and tight fitting cap therefor and having a discharge spout along its lower front edge, a transporting handle for said receptacle containing a double arm lever pivotally connected with said handle near the forward end, a connecting rod pivotally connected with the forward lever arm and threaded at the other end so as to pivotally engage a supporting means 15 for a roller, said supporting means being pivotally fastened to said receptacle, and a thumb screw moveable along the threaded length of said connecting rod and having an extended sleeve surrounding said connecting rod and housing a spiral 20 spring also surrounding substantially the same length of said connecting rod.
